(57) **CLAIM**

The ornamental design for a hood side panel, as shown and described.

DESCRIPTION

FIG. 1 is a perspective view of a hood side panel according to our new design;

FIG. 2 is a top plan view of the hood side panel of FIG. 1; FIG. 3 is a front elevational view of the hood side panel of FIG. 1; and,

FIG. 4 is a left side elevational view of the hood side panel of FIG. 1.

The right side of the hood side panel is unornamented.

FIGS. 1-4 illustrate a first embodiment of our novel design suitable for use on the left side of a vehicle. Our novel design also includes a second embodiment suitable for use on the right side of a vehicle, which is mirrored symmetrical to FIGS. 1-4 and therefore not separately illustrated.

The broken lines shown in the drawings illustrate portions of the hood side panel that form no part of the claimed design.

1 Claim, 3 Drawing Sheets
